UNITED STATES PATENT OFFICE.

HENRY H. DYER, OF SOMERVILLE, MASSACHUSETTS.

PIPE, CIGAR-HOLDER, OR THE LIKE.

1,090,036.

Specification of Letters Patent. Patented Mar. 10, 1914.

Application filed February 12, 1913. Serial No. 747,941.

To all whom it may concern:

Be it known that I, HENRY H. DYER, a citizen of the United States, residing at Somerville, in the county of Middlesex and State of Massachusetts, have invented certain new and useful Improvements in Pipes, Cigar-Holders, or the like, of which the following is a specification.

The present invention relates to improvements in smoking articles such as pipes and holders for cigars or the like, the object in view being to provide means for cooling the smoke and collecting the nicotin from the tobacco, and in this manner permit prolonged use of such article because of the ease with which the device may be removed and cleansed. It is well known in this art that nicotin from tobacco smoke possesses great moisture absorbing properties, quickly liquefying, and in the constant use of pipes or holders, this nicotin gradually collects throughout the smoke passage and the tobacco bowl, finally causing said pipe or holder to be discarded. In the ordinary construction of these devices, the nicotin in liquid form is free to collect in the smoke passage and in the action of smoking, the concentrates are drawn into the mouth of the smoker with much unpleasantness, and it was, therefore, my object to provide such an arrangement or attachment as would eliminate these disadvantages by permitting ready cleansing as well as providing a cool dry smoke so much desired.

To this end, and in order that the device may be universally adapted for use with various pipes, the preferred embodiment of my invention comprises a body portion which is adapted to be inserted in or connected with the stem of a pipe or holder and is provided with a smoke cooling chamber and nicotin reservoir, the employment of my attachment not requiring any special construction of stem to permit of its use in either old or new smoking articles.

For a full understanding of the present invention, reference is to be had to the following description and the accompanying drawings, in which—

Figure 1 is a side elevation of a pipe provided with my attachment connected to the stem. Fig. 2 is a similar view with a portion of the stem shown in section to bring out more clearly the details of construction. Fig. 3 is an enlarged sectional view taken about on the line 3—3 of Fig. 2. Fig. 4 is a similar view taken about on the line 4—4 of

Fig. 2, and Fig. 5 is a view partly in section showing the adaptation of my invention to a straight pipe or cigar holder.

Throughout the following detail description and on the several figures of the drawings, similar parts are referred to by like reference characters.

Referring to the drawings and specifically describing the invention, the body portion 1 of the attachment is provided with a longitudinal central bore 2 arranged to communicate when said body forms a section of the pipe stem 3 with the smoke passage 4 leading into the tobacco bowl or chamber 5. As most clearly shown in Fig. 2 of the drawing, the body portion is formed with a reduced tapered end portion 6 whereby to connect the same with the stem 3, at one end, and at its other end the bore 2 is internally threaded so as to receive the mouthpiece 7 in the usual manner. At a point intermediate the length of the bore 2 in the body portion 1 is formed a transverse partition 8 interrupting the passage through the stem and designed to direct the smoke drawn through the smoke passage 4 into the cooling chamber with which the attachment is provided. This chamber, designated by the numeral 9, is formed by a cap 10 preferably of metal and of any desired ornamentation, which cap is pivotally mounted as shown at 11 on one end of an upstanding or raised portion of the upper surface 12 of the body portion 1. The lower edge portion of the sides of the cap 10 are slightly crimped inwardly so that when the cap is in closed operative position the crimped edges 10' will engage in a groove formed in the sides of the raised portion 12, said groove conforming to the crimped portion 10' as shown most clearly in Figs. 3 and 4. This construction permits frictional engagement of the cap over the raised portion 12, effectively closing the cooling chamber 9 which communicates with the bore 2 at each side of the partition 8 through the short tubes 13, said tubes extending preferably slightly above the upper surface of the upraised portion 12.

It will be obvious that as the smoke is drawn through the stem of the pipe or holder, it is directed first into the cooling chamber 9 by means of the partition 8, the passage through which eliminates also the likelihood of drawing any of the tobacco particles into the mouth. The natural collection of nicotin concentrates passes down the mouthpiece as formed and are prevented

from descending into the tobacco bowl 5 by the partition 8 which thus performs a dual function. In order that the nicotin in its liquid form may not collect against this 5 partition, I provide a nicotin reservoir in the attachment which consists of a tube 14 which is inserted in the bottom of the body portion 1 directly adjacent the partition 8 so as to communicate with the upper division 10 of the bore 2 in said body portion. This tube or reservoir 14 is preferably threaded so as to receive a screw cap 15 suitably formed with a manipulating enlargement 16 by means of which the nicotin 15 may readily be emptied from the stem at any time it is desired to cleanse the same.

I have so constructed the attachment which constitutes my invention that it may readily be cleansed throughout and for this 20 purpose a tapered plug 17 is preferably provided, the same being inserted in a transverse opening through the body portion 1 which opening passes directly through the lower division of the bore 2 adjacent the 25 partition 8 as most clearly shown in Figs. 2 and 4 of the drawings. It will be obvious that in certain constructions of pipes or 30 holders with which this attachment may be used a cleaning member may readily be inserted in the opening through the tobacco chamber, or through the opening in which the plug 17 is inserted, depending upon the 35 particular construction of said pipe or holder. It is also apparent that the passages 40 13 leading into the smoke chamber 9 may be cleared by raising the free end of the cap 10, a projection 10' being formed at the upper edge of the cap and designed to facilitate raising by catching hold of the same 45 with the finger nail.

In Fig. 5 I have shown my attachment as connected with a straight pipe 18 which is formed with a tobacco chamber 19 at one end. The mouthpiece 20 is screwed onto the 45 body portion 1 while the pipe 18 is connected in like manner to the other end. The straight pipe 18 in this construction is preferably formed with a screw cap 21 adjacent the end in which the tobacco chamber is located, which cap may be removed when it is desired to clean out the smoke passage 22 extending through said pipe. This construction readily permits the passage into the body portion 1 of the attachment to be 50 cleared in the event it becomes stopped as it would obviously be difficult to pass a cleaning member through the chamber 19 without taking the attachment off. In this manner it will be apparent that the pipe 55 or holder may be so constructed that the body portion 1 forms an integral portion of the pipe and advantage is taken of the straight pipe construction with its remov-

able cap 21 whereby on removal of the cap 21, a cigar holder is formed, the end of the 65 cigar 23 being inserted into the end of the pipe 18 and projecting across the tobacco chamber 19 so as to permit the suction to draw the smoke into the smoke passage 22.

From the foregoing description the advantages of my invention will be appreciated and it need only be said in conclusion that the attachment constituting my invention may be manufactured and sold as such so that it might be employed in an old or 75 used pipe as well as provided in the stem of a newly manufactured holder or pipe.

Slight changes may be readily made in the details of construction of my attachment without departing from the spirit of the invention, and within the scope of the appended claims.

Having thus described my invention, what I claim as my invention and desire to secure by Letters Patent is:

1. As a new article of manufacture, an attachment comprising a body portion adapted to be connected to a pipe or holder, said body portion having an interrupted passage therethrough, a raised portion formed on 90 said body portion, a cover pivotally connected at one end to the raised portion aforesaid and adapted when in closed position to form a smoke cooling chamber, smoke passages connecting the interrupted bore with the 95 smoke cooling chamber, a nicotin reservoir carried by the body portion, for draining one portion of the interrupted passage aforesaid, and a removable member projecting into the other portion of the passage to 100 permit cleansing of the same.

2. As a new article of manufacture, an attachment comprising a body portion adapted to be connected to a pipe or holder, the body portion having an interrupted passage therethrough, a raised portion formed on said body portion, a cover pivotally connected at one end to the raised portion aforesaid and adapted when in closed position to form a smoke cooling chamber, smoke 105 passages connecting the interrupted bore with the smoke cooling chamber, the body portion aforesaid having a transverse opening therethrough communicating with one portion of the interrupted passage, a removable plug normally received in said transverse opening, and a nicotin reservoir carried by the body portion and communicating with the other portion of said interrupted 110 passage.

In testimony whereof I affix my signature in presence of two witnesses.

HENRY H. DYER.
